ATTORNEY.

UNITED STATES PATENT OFFICE.

MAX KAPPNER, OF CINCINNATI, OHIO.

ARCH-SUPPORT FOR THE HUMAN FOOT.

1,395,498.

Specification of Letters Patent.

Patented Nov. 1, 1921.

Application filed April 26, 1920. Serial No. 376,611.

To all whom it may concern:

Be it known that I, MAX KAPPNER, a citizen of the United States, residing at Cincinnati, in the county of Hamilton and State 5 of Ohio, have invented new and useful Improvements in Arch-Supports for the Human Foot, of which the following is a specification.

My invention contemplates a support for 10 the arch of the human foot whereby, when weakened from any cause, the strain upon the ligaments connecting the bony structure may be relieved and nature assisted in their restoration.

15 The bony structure of the foot embodying three sections or groups of bones known as the tarsus (including the os calcis or heel); the metatarsus (or arched section); and the phalanges (or toe section), takes the weight 20 of the body upon the first and third of these groups, flexibly connected by the arch of the middle group. The various small bones of these sections are held together by muscular ligaments, and the entire system is 25 underlaid and connected fore and aft by layers of muscular tissue attached primarily to the os calcis, terminating forward in flattened tendons connected to the phalanges and the forward bones of the metatarsal 30 group.

These muscles furnish the motive power giving various motions to the foot in relation to the socketed connection with the tibia or leg bone. This relation is such that, 35 practically the greater part of the weight of the body is carried into the foot structure and concentrated normally at the high point of the arch, thus giving a flexible or yielding resistance to impact under proper conditions of use.

From various causes, the connecting tissues of the arch-bones become weakened by over-strain, resulting in what is known as the "breaking down" of the arch, allowing 45 the foot to turn at the ankle and sag downward at the inside of the instep,—a condition developing into typical "flat foot" with attendant evils of tired and aching feet, weak ankles, cramped toes, etc., seriously 50 impairing the ability to walk.

The common attempt to prevent or remedy this condition by inserting a simple piece of elastic sheet metal in the shoe-sole; or,

worse, a built up and unyielding arch support, is based upon ignorance of the actual 55 conditions and often aggravates rather than relieves the evil.

My invention is intended to provide an external appliance in the nature of an artificial support, adapted to the conditions 60 found to exist, by its form and structure and mode of use, susceptible of slight manipulation to suit the conditions of the immediate case and furnish an efficient artificial support tending to relieve the evils of weakened foot-arch and to provide conditions 65 tending to complete restoration.

To this end the device consists of an artificial arch-support for the human foot, of suitable shape—approximately as herein illustrated;—adapted to bear upward against the bottom of the foot over the space occupied by the metatarsal and forward part of the tarsal bones as shown in Fig. 3. The support is arched slightly lengthwise and 70 also in part crosswise, to conform to the natural curvatures of the foot; and is provided at one side with an upwardly curved edge portion to support the instep, and is 75 preferably perforated with air apertures to 80 allow a circulation of air sucked in and expelled by the movements occasioned by walking. It is preferably also formed with slight depressions at the bearing points of contact with the earth, especially of the cuboid, the internal cuneiform, and the scaphoid bones, and thus relieve any abnormal 85 pressure and secure a properly cushioned seat for the foot upon the underlying muscular tissue with equalized and even pressure, 90 supporting all arches of the same.

My invention is illustrated in the accompanying drawings, in which—

Figure 1 is a view in perspective of the bony structure of the human foot showing 95 the under side as it would appear on being lifted from the plate shown in the next figure and turned back;

Fig. 2 a plan view of the artificial support of the arch of foot with dotted lines 100 indicating structural features to be explained;

Fig. 3 a side elevation of the foot resting upon a plane surface and showing the artificial support in position relating thereto; 105 Fig. 4 a diagrammatic cross section of the

normal foot through the metatarsal bone-group near the head, showing their cross or lateral arching relation constituting the "hollow" of the foot; and

5 Fig. 5 a detached plan view of the "strengthener" for insertion as a chord to the longitudinal arch of the device shown attached in Fig. 3.

In the drawings, the general bony structure 10 of a left human foot designated by the reference letter "A" in Fig. 1, is shown in relation to the arch support "B", Fig. 2, as though lifted off the latter and turned over backward. The support "B" is cut from an 15 elastic material preferably sheet metal, of the general form indicated, to cover the under side of the foot-arch formed by the associated metatarsal and cuneiform bones; and is slightly arched fore and aft to 20 conform to the natural arch of the foot in normal condition.

At the instep side of the foot, the support "B" is rounded upward as at "b" to give especial support to the instep and prevent 25 the tendency to sag downward as hereinbefore mentioned.

The upward bend thus formed is supplemented in a slight upward bend on a longitudinal line within the general body of the 30 plate constituting a trough extending rearwardly from the front edge of the plate B beneath the first metatarsal and dying out at the rear of the scaphoid bone. This trough, being independent of the general 35 cross-curvature of the plate B and having a sharply recurved inner wall, serves, by its lateral contact beneath and against both sides of the first metatarsal internal cuneiform and scaphoid bones, to hold the supporting plate in proper contact relation with the foot. At the contact projections of the 40 bones named, in said trough, shallow socket-like depressions d^1 d^3 are provided. These depressions simply emphasize at certain 45 points the general "hollow" of the trough in which they are contained. At the opposite side of the plate B a somewhat deeper and larger socket-like depression d^2 is provided for the cuboid bone. There is thus 50 constituted a system of support underlying the os calcis and extending and having its greatest effect in the tarsus, extending also well beneath the metatarsus group, but terminating behind the phalangeal jointures. 55 At the outer side the support is continued longitudinally beneath the fifth metatarsal with the principal bearing in the cuboid socket d^2 . The general area of support thus 60 includes the central and cross-arching of the plate curvatures beneath the bony system; and gives equal and elastic support to all parts.

In walking, the pressure of the foot upon the supporting arch is intermittent, frequently to the extent of relieving actual

contact pressure; and, in order to utilize this as a means of ventilation between the under surface of the foot and the support "B", the latter is punctured with numerous holes "c" through which air may be thus 70 drawn and expelled. The introduction of air in this manner tends to relieve the heat and moisture incident to prolonged contact in this condition, and assists nature in the 75 restoration of the ligament functions of the connecting tissues of the bony structure.

A further feature of the invention recognizes the importance of adapting the arch structure to a surface of contact with the foot in which a uniformity of foot-pressure 80 may be attained, spread uniformly over the bony contact surface cushioned by the underlying muscular system. To this end shallow depressions "d" are provided, located to accommodate bony protuberances 85 found to exist, so as to relieve the concentration of pressure otherwise caused, and spread the same over the surrounding tissue. These depressions are easily produced by means of a small peening hammer and anvil 90 or otherwise, as required. The outer edge of the plate B including a narrow margin is turned slightly downward for the double purpose of adding to the resilient stiffness and also forming an edge-contact line for 95 holding the plate against the sole of the shoe and by consequence in proper relation to the foot.

To further hold the device in its proper position in relation to the foot, I provide 100 a sharp pointed projection at the rear, preferably by cuts in the material, in V-shape, and bent to a vertical position downward. The weight of the foot upon the os calcis bone forces the projection into the material 105 of the shoe sole and thus retains it in proper position in the shoe.

I may also employ where necessary or desirable a small piece of metal "g" affixed to the device "B" as a chord to the arc 110 formed by the arch, as shown in Figs. 3 and 5; and where desirable, also, in relieving the impact of the os calcis in walking, I may attach a small cushion of resilient material at the under side of the plate "B" 115 conforming to the curvature of the rear end of the plate as indicated by dotted lines in Fig. 2 at f. This also assists in the circulation of air in the manner hereinbefore indicated.

125 I claim and desire to secure by Letters Patent of the United States:

A foot-arch support for the human foot consisting of a somewhat flexible plate conformed in general outline to cover the 125 underside of the normal arched portion of the foot and rest at its ends upon the external shoe sole, having a bent up inner side of the plate extending into and forming a narrow trough with a swaged-up portion of 130

the plate as a rest and seat for the downward projections of the rear-enlargement of the first metatarsal, the internal cuneiform, and the scaphoid bones; and having a socket depression near the outer side of the plate for seating the cuboid bone.

5 In testimony whereof I have hereunto set

my hand in presence of two subscribing witnesses.

MAX KAPPNER.
